UNITED STATES PATENT OFFICE.

NORMAN A. ROBERTSON, OF NEW YORK, N. Y.

METHOD OF BENDING AND DRAWING SHEET METAL.

1,078,958.

Specification of Letters Patent.

Patented Nov. 18, 1913.

Application filed May 8, 1912. Serial No. 695,881.

To all whom it may concern:

Be it known that I, NORMAN A. ROBERTSON, a citizen of the United States, residing in the borough of Brooklyn, county of Kings, city and State of New York, have invented certain new and useful Improvements in Methods of Bending and Drawing Sheet Metal, of which the following is a specification.

10 This invention aims to provide an improved method of bending and drawing sheet metal, such for example as iron or steel or aluminum, and especially for drawing the irregularly-shaped parts of the bodies of automobiles and similar vehicles.

Automobile bodies usually comprise a supporting floor, and sides and ends which enclose the seats. The sides and ends have been made of plates of metal some or all of 20 which are bent both in a longitudinal and in a transverse direction so as to produce convenient and graceful shapes. Except at the corners between the sides and the ends the curvature of the plates has been comparatively slight, and it has been the practice heretofore to shape the plates by hand, at a very considerable expense.

25 This invention provides for the drawing of the plates into the desired shape entirely by machinery, thus securing greater accuracy and economy than can be secured by hand work.

In the accompanying drawings, Figures 1, 2 and 3 are respectively an elevation, inverted plan, and section (on the line 3—3 of Fig. 1) of a plate adapted to form the rear end of an automobile body; Figs. 4, 5, 6 and 7 illustrate a suitable machine for making the end plate of Figs. 1, 2 and 3; Fig. 4 being 30 a front elevation, partly in section, Fig. 5 being a horizontal section on the line 5—5 of Fig. 4, Fig. 6 a central transverse section, and Fig. 7 an end elevation.

The article shown in Figs. 1, 2 and 3 is an 35 unfinished end plate or seat back and is selected as typical of the numerous different shapes which can be made according to the principles of this invention. Calling the distance from right to left in the drawing the

length of the sheet, Fig. 2 shows that it is 50 curved longitudinally to form the center A and the end portions B at approximately a right angle to the central portion; and Fig. 3 shows that the central portion is curved transversely, the curve being of slight degree and being of reversed or S-shape. 55 Adjacent to the upper and lower edges of the plates are stiffening ribs C and D stamped therein. Similar intermediate ribs F are formed in the back or central portion. The 60 ends of the plate are unfinished, being subsequently trimmed and bent in any usual or suitable press.

In shaping the plate, the blank is held at 65 two opposite sides, and left free at the other two sides. For example, for making the plate of Fig. 1 it would be held only at the end portions B. Notwithstanding that the blank is free at the top and bottom sides, it is drawn into a shape which is curved in the 70 transverse direction as well as in the longitudinal direction, the holding of the ends being sufficient to permit the limited amount of transverse shaping required. It is possible in fact to secure most of the shapes desired by the mere pressure of the shaping 75 punch upon one face of the sheet, without the necessity of an opposing die, the desired shape being obtained by the mere stretching of the metal over the punch by reason of 80 the relative movement between the punch and the clamped ends of the blank.

Various types of machine may be used for 85 securing the clamping of the ends of the blank and the desired relative movements of the punch, clamps, and die. In the machine illustrated a pair of blank holders or grippers G are located at each side of the machine, being removably mounted on blocks H which are mounted, one at each side of the 90 machine, on the upper ends of a pair of plungers H' which work in hydraulic cylinders J; the blocks H at opposite sides being connected to each other by means of cross bars K, and the cylinders J being mounted 95 on a cross-head or platen L on the top of the plunger M of the main ram by which the punch N is raised and lowered. The upper

die O is fixed in the upper press head O' and carries removable grippers P. The upper grippers P and the lower grippers G are made detachable, so that grippers of different shapes may be put into the machine for making plates having differently shaped ends.

The cylinders J are connected to any usual or suitable type of accumulators whereby a constant hydraulic pressure is maintained on the plungers H, this pressure being calculated to permit a drawing of the sheet Q through the grippers with considerable friction as the punch advances, and being adjustable to different pressures. The punch N is mounted on a frame R which is provided with projecting lugs S which engage the upper edges of the tie bars K so as to hold the grippers G away from the blank until the punch commences to advance; after which the blank is gripped with a constant pressure during the entire drawing operation, the lugs S rising clear above the tie bars K. The punch N and die O are removable like the grippers P and G to adapt the machine for bending plates of different shapes. While other types of machine may be used, the machine illustrated is especially designed for the work in question and has substantial advantages in doing such work. The attachment of the cylinders J to the ram makes a perfectly simple and very strong construction which works automatically to first clamp the blank and then draw it while holding its ends with a substantially constant pressure sufficiently slight to prevent tearing the blank. The grippers G are inclined on their ends and there is consequently a strong lateral force acting against the grippers and the blocks H. But these blocks bear inward against the punch N and are thereby absolutely held against yielding. The ends of the blank may be quite long and weighty and the faces of the grippers G and P are inclined to give a substantial downward incline to the extending ends of the blank, thus minimizing the difficulty of drawing them through the grippers.

The blank Q being placed in the machine, its ends are gripped with a determined pressure at the first upward movement of the punch. During the further movement of the punch the ends, though permitted to slip as far as necessary, are held with considerable firmness, so that they first draw the comparatively thin metal closely over the punch and make it fit the punch, somewhat in the manner in which a new glove is drawn over one's hand, and thereafter permit the ends to slide through the grippers as the punch advances. I prefer to provide ribs T on the punch and corresponding grooves U on the die, for forming the stiffening ribs

in the plate; because the ribs T on the punch appear in practice to give the punch a better grip on the sheet even before the latter is pressed clear up to the die. To secure the general curves desired it is not necessary to press the sheet clear against the die, the drawing of it over the punch, alone being sufficient with some shapes and metals. In other cases it may be made to bear against the die where the shape desired is difficult to secure otherwise. Or, as in the case illustrated, the punch may be made to carry the blank against the die throughout the entire area of the blank, and such contact is necessary to form the sharply curved stiffening ribs of the plate shown in Figs. 1, 2 and 3. After the drawing operation in the machine illustrated, the ends of the blank may be trimmed and further bent, drawn, or stamped as desired. For example, end extensions B' and end ribs C' D' and E may be formed as shown, in dotted lines, in Figs. 2 and 3.

I do not claim the apparatus above described in the present application, the same being claimed in a divisional application, pending concurrently herewith.

What I claim is:—

1. The method of bending and drawing sheet metal to make parts of vehicle bodies or the like which are curved in two directions and are formed with stiffening ribs, which method consists in pressing a blank between a punch and a die shaped to perform the desired drawing and bending operations and to stamp the stiffening ribs all at one operation, holding the blank at two opposite sides, and leaving it free at the other two sides.

2. The method of bending and drawing sheet metal to make parts of vehicle bodies or the like, which consists in holding two opposite ends of a blank and drawing it over a suitably shaped punch, to cause it to fit the shape of said punch, and thereafter pressing it between said punch and a die of suitable shape, releasing its ends sufficiently to permit them to move with the punch.

3. The method of bending and drawing sheet metal to make, in a single operation, parts of vehicle bodies or the like which are curved in two directions, which consists in yieldingly gripping two opposite sides of the blank while leaving it free at the other two sides, and drawing it to the desired shape by stretching it over a punch having a face of the required contour, and thereby drawing the metal unequally between its gripped edges to bring it into conformity with such contour.

4. The method of bending and drawing sheet metal to make, in a single operation, parts of vehicle bodies or the like which are

curved in two directions, which consists in yieldingly gripping two opposite sides of the blank while leaving it free at the other two sides, and drawing it to the desired 5 shape by stretching it over a punch having a face of the required contour, and thereby drawing the metal unequally between its gripped edges to bring it into conformity with such contour, and finally squeezing the

sheet between said punch and a die con- 10 formed thereto.

In witness whereof, I have hereunto signed my name in the presence of two subscribing witnesses.

NORMAN A. ROBERTSON.
